PLOWPOINT

Filed Sept. 14, 1925

Inventor
Charles S. Coleman;
By
R. S. Berry
Attorney.

UNITED STATES PATENT OFFICE.

CHARLES S. COLEMAN, OF LOS ANGELES, CALIFORNIA.

FLOWPOINT.

Application filed September 14, 1925. Serial No. 56,167.

This invention particularly pertains to a plow having a renewable point and working edge.

An object of the invention is to provide 5 a plow in which the point as well as the edge which are subject to rapid abrasion may be readily removed and replaced.

Another object of the invention is to provide 10 a construction in plows of the above character in which a two piece share is employed, one of these pieces being secured to the mold board and normally permanent and the other piece being renewable and secured to the permanent piece and providing 15 the point and cutting edges.

A further object of the invention is to provide 20 a construction in plows of the above character whereby renewable cutting members of the share may be securely affixed to the permanent member and held against accidental displacement thereon yet be readily detached for sharpening or replacement when excessively worn.

The invention resides generally in the construction 25 of the joint or connection between the permanent member and the removable and renewable member, as hereinafter fully set forth and defined in the claim.

The accompanying drawing illustrates the 30 invention in its preferred embodiment, in which:

Figure 1 is a view in perspective of the permanent member of the share;

Figure 2 is a view in perspective of the 35 removable member of the share which provides the renewable point and edges thereof;

Figure 3 is a view in section as seen on the line 3—3 of Figure 2;

Figure 4 is a view in side elevation of a 40 completely assembled plow embodying the members shown in Figures 1 and 2 secured to a mold board;

Figure 5 is a view in vertical section as seen on the line 5—5 of Figure 4.

In carrying out my invention I employ a 45 permanent share member 10 and a removable share member 11 adapted to be secured together to form a complete plow share 12 as shown in Figure 4, the permanent member 50 of the share being secured to a usual type of mold board 13, to form a complete plow 14. These parts may be designed to form a plow of any suitable character according to the service for which it is required but is here shown as designed for 55 general soil breaking purposes. The re-

newable member of the share is provided with the requisite point 15, and side edge 16, and provides the means for renewing the point and edge. The permanent member 10 is adapted to be secured to the mold board 13 in any suitable manner but is here shown as attached thereto by bolts 17.

The permanent member 10 is formed with a straight lower edge from which projects 60 a marginal side flange 18 spaced from the front face of the member to form a straight continuous shoulder 19 at the base of the flange; the flange 18 extending from the extreme rear end of the member to a point 65 spaced inwardly from the front end thereof and terminating in an end shoulder 20. The outer edge 21 of the flange is straight and extends parallel with the shoulder 19. The front end of the member 10 is inclined rearwardly and is formed with an end flange 22 70 extending toward the land side of the share, and diverging rearwardly from the point a or front edge of the plow at an acute angle. This flange 22 is formed integral with the permanent member and extends along the forward end thereof from the lower horizontal edge in continuation of the shoulder 19 and projects toward the upper edge of the member a suitable distance and increases 75 in width upwardly. The front surface of this end flange presents a smooth face against which a corresponding part of the renewable member abuts to provide a rigid joint as hereinafter explained, and formed 80 thereon is a shoulder 23, which extends transversely across and projects outwardly from the front of the end flange.

The renewable blade member is formed 85 with a straight horizontally extending upper edge 24, adapted to abut against the shoulder 19 throughout the length of the permanent member, and the inner surface of the renewable member is provided with a shoulder 25, against which the lower edge 21 of the flange 18 abuts, this construction providing a flange 90 26 along the upper edge of this member 11 adapted to overlap the flange 18 on the member 10 to form a lap-joint between the two 95 assembled members as particularly shown in Figure 5. This lap-joint brings the front and rear surfaces of the share members flush with one another to present a smooth surface to the soil and to reduce the tendency of abrasion at the joints from the action of 100 the soil.

The renewable blade member is also pro-

vided with an end flange 27, formed integral therewith and shaped to conform to the outer face of the flange 22 on the permanent member. This flange 27 diverges from the front edge *b* of the share at the requisite acute angle but extends upward above the member so that when this member is secured to the permanent member the projecting portion of this flange extends to abut against the shoulder 23 on the permanent member. It will be observed that this flange provides an upper forward edge of the plow which edge is subject to wear at points well upward on the share, so that this edge being provided on an integral part of the renewable member is renewed together with the other edges subject to wear. A ledge 28 is formed on the rear face of the flange 27 and extends transversely thereof in continuation of the upper edge 24, which ledge is adapted to abut against the lower end of the flange 22 on the permanent member, and formed on the back of the membe^r 11 is a vertical shoulder 29 leading from the shoulder 25 to the edge 24 which shoulder is adapted to abut against the end 20 of the flange 18 on the permanent member.

The rear face of the flange 27, abutting against the forward face of the flange 22 on the permanent member tends to hold the parts more securely together, particularly since the forward motion of the plow through the soil creates a thrust which will tend to hold the parts more securely together adding to the rigidity of the assembled share.

It will be noted that the edge 24 and ledge 28 form a continuous abutment adapted to bear throughout the length of the shoulder 19 and the flange 22 of the permanent member and that the shoulder 25 forms an abutment for the lower edge 21 of the flange 18 so that edge thrusts on the renewable member will be opposed throughout the permanent member in the same manner as though the renewable and permanent members were made in one piece.

When the two members of the share are

assembled as shown in Figures 4 and 5 all joints between the two members present a smooth surface. The flange 27 extending upward to the shoulder 23 provides a protection for the permanent member against abrasion from the soil. The renewable member 11 is provided with countersunk holes 30 in the flange 26 which register with holes 31 in the flange of the permanent member. Rivets 32 are passed through these holes and headed to securely clamp the members together. Bolt holes 35 and 36 are formed in the end flanges 22 and 27 respectively to receive bolts 37 which aid in further securing the members together.

Whereas I have shown and described a specific embodiment of my invention I do not limit myself to the exact details of construction shown but may employ other constructions and modifications thereof, without departing from the spirit of the invention, coming within the scope of the appended claim.

I claim—

In a plow of the class described, a renewable plow share and point comprising a unit for attachment to an unaltered fixed share of a plow, the lower edge of said unit being reduced in thickness for a portion of its length only to provide both longitudinal and lateral shoulders, a flange formed at the forward end of the member extending toward the land side and a shoulder formed on said flange whose forward end terminates short of the forward margin of the flange, a second unit comprising a plow point and cutting edge having a point extension for overlapping the flange and shoulder of the first unit and its upper portion reduced in thickness and provided with a shoulder for engagement and connection with the recited lower edge and shoulder of the first unit, and means for detachably connecting the recited edges of the two units.

In testimony whereof I have hereunto affixed my signature.

CHARLES S. COLEMAN.
